PRESERVATION OF PAINT BRUSHES

George Claude, New York, N.Y.

Application June 3, 1957, Serial No. 663,019

4 Claims. (Cl. 206—15.1)

The present invention relates to receptacles for special purposes and, more particularly, to a method of and a receptacle for storing paint brushes when not in use to prevent the same from hardening.

One of the problems of painters is to keep their brushes in a soft and pliable condition from the end of one working day to the beginning of the next, as well as over extended periods. The usual practice has been to clean the brushes at the end of the day with a paint solvent hoping that they remain in good condition until they are to be used again.

This method of cleaning paint brushes is unsatisfactory for several reasons. Washing the brushes with a paint solvent does not remove all the paint between the bristles, particularly at the base where the bristles are held tightly together by the setting for mounting them on the handle. Thus, if the brushes are not used again within the next day or so, the unremoved paint stiffens the bristles.

Any attempt to vigorously clean the bristles, especially after paint has dried between them and has rendered them stiff, results in bristle breakage which shortens the useful life of the brush. These difficulties are serious because painters usually have a large number of brushes for different types of work and in many cases only a few brushes are used every day while the others may not be required as frequently, whereby stiffening thereof cannot be averted.

Consequently, painters wear out their brushes at a rapid rate and are faced with the expense of frequently replacing the same. Needless to mention, brushes used by professional painters are quite costly.

Heretofore, it has been proposed to prevent paint brushes from hardening by providing a receptacle closed by a cover and containing a pool of paint solvent in which the bristles of the brushes were immersed by suspending the bristles from a rack. The difficulty with such kits was that the paint solvent increased the weight of the kit and sloshed over the brush handles. Also, the paint solvent by being in constant contact with the brush settings deteriorated the same. After the brushes were so immersed, they were unfit for use until practically all the paint solvent was removed from the bristles, because otherwise the solvent would dilute the paint and cause the brushes to drip at the handle to make them unworkable. Here again, the vigorous action required to remove the solvent caused bristle breakage. Consequently, such kits have never met with success in the trade.

Accordingly, an object of the present invention is to provide a receptacle for storing paint brushes when not in use during the day or from day to day which overcomes the foregoing difficulties and objections.

Another object is to provide such a receptacle which maintains the brushes in good condition over a long period of time and thereby lengthens the useful life thereof.

2

Another object is to provide such a receptacle for storing a large number of paint brushes in a compact and orderly manner and to render them readily accessible for use.

5 A further object is to provide such a receptacle which pays for itself many times by the number of brushes it saves.

A still further object is to provide a method for accomplishing the foregoing in a simple, practical and 10 economical manner.

Other and further objects will be obvious upon an understanding of the illustrative embodiment about to be described, or will be indicated in the appended claims, and various advantages not referred to herein will occur to 15 one skilled in the art upon employment of the invention in practice.

In accordance with the present invention, the foregoing objects are accomplished by providing a box-like receptacle having a drip pan at the bottom thereof and having 20 racks or hangers therein for suspending a large number of paint brushes and having a cover which is securely attached in a convenient manner to hermetically seal the receptacle, whereby an atmosphere of paint solvent is established within the receptacle which maintains wet paint 25 brushes in soft and pliable condition for a month or more.

A preferred embodiment of the invention has been chosen for purposes of illustration and description and is shown in the accompanying drawing, forming a part of the specification, wherein:

30 Fig. 1 is a perspective view of a receptacle in accordance with the present invention.

Fig. 2 is a sectional view taken along the line 2—2 on Fig. 1.

Fig. 3 is a sectional view taken along the line 3—3 on 35 Fig. 1.

Fig. 4 is a sectional view taken along the line 4—4 on Fig. 3.

Fig. 5 is a fragmentary exploded perspective view illustrating the cover removed from the receptacle.

40 Fig. 6 is a fragmentary sectional view illustrating a pivotal and sealing arrangement for the cover.

Fig. 7 is a perspective view of a stand for supporting brush racks or hangers adapted to be placed into the receptacle.

Fig. 8 is a perspective view of a brush rack and hanger 45 arrangement.

Fig. 9 is a perspective view of a multiple brush hanger.

Referring to the drawings in detail, there is shown a brush preserving kit in accordance with the present invention which generally comprises a receptacle 10 having an open top, a cover 11 for the receptacle, a pan 12 in the receptacle, a stand 14 in the receptacle and racks 15 supported by the stand for suspending paint brushes B by their handles with their bristles down (Figs. 2 and 3).

55 As shown herein, the receptacle 10 is an oblong, rectangular box-like structure having a bottom 16, a front wall 17, a back wall 18 and side walls 19. For the purpose of cooperating with the cover 11 to provide an airtight seal for the interior of the receptacle, the front and side walls have horizontal inwardly extending flanges 20 and 21, respectively, at the upper ends thereof and the back wall 18 has an inwardly extending raised flange 22 (Figs. 2, 3, 5 and 6). This raised flange 22 is provided by extending the back wall and the rear portions of the side walls upwardly above the front wall and the side flanges 21. The side flanges terminate short of the back wall (Fig. 5 and 6) and the raised flange 22 is spaced rearwardly therefrom to provide openings for the cover, as about to be described.

The cover 11 has depending front and side portions 24 and 25 for receiving the upper end of the front and side walls, with the side portions 25 terminating at the raised flange 22 (Figs. 1, 5 and 6), and the cover has a back portion in the form of an upwardly facing channel 26. Sealing means 27 and 28 are mounted on the underside of the cover for respectively overlying and engaging the front and side flanges 20 and 21, with the side flange sealing means 28 extending from the front flange sealing means 27 to the inner flange of the channel 26. Sealing means 29 are mounted in the channel 26 for engaging the underside of the raised flange 22.

The cover 11 is applied to the receptacle by inserting the ends of the back of the channel into the space between the rear end of the side flanges 21 and the raised flange 22 and moving the cover forwardly and downwardly from the position shown in Fig. 6 to that shown in Fig. 1, whereby the sealing means 29 in the channel slides under the raised flange 22 and the front and side sealing means 27 and 28, respectively, overlie the flanges 20 and 21, respectively.

The sealing means are brought into sealing engagement with their respective flanges by applying downward pressure at the front of the cover, for example, by hasp means 30 at the front of the receptacle and the cover.

The receptacle and cover arrangement just described provides an airtight seal for the interior of the receptacle in a simple and practical manner and at the same time eliminates the cost of hinges and the expense of providing adequate sealing means for hinged covers. The cover also is readily removable and replaceable, and the necessary sealing pressure is supplied simply by fastening the hasp means 30.

The drip pan 12 (Figs. 2, 3, 4 and 7) preferably is rectangular and has a bottom 31 and front, back and side walls 32, 33 and 34, respectively. The height dimension of these walls is much less than that of the length and width dimensions of the bottom, whereby the pan is relatively shallow. Actually, these walls could be much shorter than shown to enable the pan to accomplish its drip collecting function, but preferably the walls are as tall as shown for the purpose about to be described.

The stand 14 (Figs. 4 and 7) is a rectangular structure including four legs 36 in the form of angle members which are snugly fitted into the corners of the drip pan and are lapped by the pan walls for a sufficient height to so retain the same. The upper ends of the legs 36 are connected by front, back and side members 37, 38 and 39, respectively, with opposite pairs of members having rack supporting means thereon of different types.

To accomplish this, the side members 39 (Fig. 7) have upwardly facing notches 40 for cooperating with downwardly facing notches 41 formed at the ends of a rack 15, such as shown in Fig. 8. This rack has spaced parallel elements 42 and 44 between the ends thereof for accommodating individual brush holders 45.

The front and back members 37 and 38 are channels having upper and lower sections 46 and 47 which are formed with aligned apertures 48 for supporting a rack 15', such as shown in Fig. 9. This rack is formed of stiff, rod-like material or wire and has depending portions 49 at its ends adapted for insertion into the aligned apertures 48 of both sections to prevent the rack 15' from turning and dropping brushes mounted thereon. The rack 15' is formed between its ends with loops 50 which serve as brush handle holders.

As shown in Figs. 2 and 3, the height of the legs 36 is such that the racks 15 and 15' are supported well above the drip pan so that the free ends of the brush bristles are spaced above the pan and do not extend into the same. With this arrangement, when the wet brushes are supported as shown and the cover is sealed on the receptacle, the paint drippings are collected by the pan 12. Since the bottom of the pan has a relatively large surface area, the paint solvent in the drippings will tend to

evaporate quite rapidly to thereby create a dense atmosphere of solvent vapors. These vapors have been found to have a sufficient density to act as a solvent for the paint remaining between the brush bristles to prevent the paint from hardening. Tests have demonstrated that the bristles are kept soft and pliable for more than a month by employing this method of preserving the same, and that the brushes are then ready for immediate use without any cleaning or other treatment whatsoever.

From the foregoing description, it will be seen that the present invention provides an arrangement for keeping paint brushes in working order for long periods of time between use without any care on the part of the painter. The kit is light in weight, even when loaded with brushes and can be carried conveniently by handles (not shown) either placed on the cover or on opposite sides.

As various changes may be made in the form, construction, and arrangement of the parts herein, without departing from the spirit and scope of the invention and without sacrificing any of its advantages, it is to be understood that all matters are to be interpreted as illustrative and not in any limiting sense.

What is claimed is:

1. A kit for preserving used paint brushes comprising a box-like receptacle; a normally empty drip pan at the bottom of said receptacle; means in said receptacle for supporting a paint brush with its bristles down above said pan; said receptacle having an open top provided with an inwardly extending flange at the front thereof, an inwardly extending flange at each side thereof extending from said front flange and terminating short of the back of said receptacle, and an inwardly extending raised flange at the back thereof spaced from the rear ends of said side flanges; a cover pivotally carried by said receptacle having depending front and side portions for receiving the upper end of the front and sides of said receptacle with the side portions of said cover terminating at said raised flange and having a back portion formed with an upwardly facing channel; sealing means at the underside of said cover for overlying and engaging said front and side flanges; and sealing means in said channel for extending under said raised flange and engaging the underside thereof.

2. A kit according to claim 1, including hasp means at the front of said receptacle and said cover for urging said sealing means downwardly on said front and side flanges and upwardly against said back flange.

3. A kit according to claim 1, wherein said drip pan is relatively shallow and said brush supporting means is a stand including removable brush supporting racks.

4. A kit for preserving used paint brushes comprising a box-like receptacle having an open top, said receptacle including front and side walls with inwardly directed flanges at the upper ends thereof and a back wall with inwardly directed flanges at its upper end elevated above said flanges of the front and side walls, said side wall flanges terminating short of the back wall and said back wall flange terminating on said side walls so as to provide an opening between said back wall flange and each of said side wall flanges, a closure for said open top adapted to provide an airtight seal, said closure including depending front and side portions for respectively receiving the upper ends of said front and side walls and a back portion with an upwardly facing channel for insertion through said opening into engagement with said flanges for pivotal movement therebetween, sealing means on said closure adjacent said depending front and side portions for respectively engaging upper surfaces of said front and side flanges and sealing means within said channel for engaging an under surface of said back wall flange when in a closed position, a relatively shallow, normally empty drip pan supported on the bottom of said receptacle, a stand in said receptacle having legs for supporting the same, and a rack supported by said stand for suspending a paint brush by its handle with its bristles down, said rack being

spaced in a vertical direction from said pan by said stand for a sufficient distance to prevent the free ends of the bristles from extending into said pan.
